GOBLET

Maxine G. Levin, Westhill Drive,
Gates Mills, Ohio 44040

Filed Dec. 11, 1972, Ser. No. 314,122

Term of patent 14 years

Int. Cl. D7—01

U.S. Cl. D7—13

FIG. 1 is a front or rear elevation of a goblet showing my new design;;

FIG. 2 is a left or right side elevation thereof;

FIG. 3 is a top plan view thereof;

FIG. 4 is a cross-sectional view thereof taken on line 4—4 of FIG. 2; and

FIG. 5 is a bottom plan view thereof on a reduced scale.

I claim:

The ornamental design for a goblet, substantially as shown.
